UNITED STATES PATENT OFFICE.

NORMAN I. MILLIKEN, OF SOUTH BEND, INDIANA. ASSIGNOR TO OLIVER CHILLED PLOW WORKS, OF SOUTH BEND, INDIANA.

GANG-PLOW.

1,095,511.

Specification of Letters Patent.

Patented May 5, 1914.

Original application filed June 19, 1913, Serial No. 774,669. Divided and this application filed September 13, 1913. Serial No. 789,586.

To all whom it may concern:

Be it known that I, NORMAN I. MILLIKEN, of South Bend, in the county of St. Joseph and State of Indiana, have invented certain new and useful Improvements in Gang-Plows; and I do hereby declare the following to be a full, clear, and exact description of the invention, such as will enable others skilled in the art to which it appertains to make and use the same.

This invention relates to an improvement in gang plows and is a division of my application No. 774,669 filed June 19th, 1913.

The object of this invention is to provide simple and efficient means for imparting independent vertical adjustment to each of the several plows of a gang plow.

With this object in view the invention consists in the features of construction and combinations of parts which will be herein-after described and pointed out in the claims.

In the accompanying drawings, Figure 1 is a view in side elevation of one of the plow beams of my improved gang plow. Fig. 2 is a plan view of the same and Fig. 3 is a side elevation of the upper portion of the plow standard.

1 represents the plow beam which is formed of the channel bars 2 and 3, and is pivotally and adjustably connected at its forward end to the plow frame.

41 represents the plow standard, the upper end of which is provided with a forwardly projecting arm 42, having an arc shaped slot 43 in its rear end, while its forward end is provided with an open slot 44 in its upper edge and a break pin hole 45 near its lower edge. Between the sides of the

40 arm and the channel beams are interposed the friction plates 46, the forward ends of which are formed with depending lugs 47, each of which is provided with a hole 48. The break pin 48^a is inserted through the

45 holes in the friction plates and the hole 45 in the arm of the standard. A bolt 49 passes through holes 50 in the channel beams and friction plates 46 and through the open slot 44 in the forward end of the standard arm 42, and serves to force and hold the outer

50 surfaces of the arm in snug frictional contact with the inner surfaces of the friction plates 46. To insure a large area of frictional contact surface the opposite sides of

the forward end of the standard arm are 55 each provided with a flat bearing surface 51 which extends the entire width of the arm.

52 is a stirrup the depending arms 53 of which are interposed between the rear end of the standard arm and the friction plates. 60 A bolt 54 passes through the channel beams, the arms 53 of the stirrup, the friction plates and the arc shaped slot 43 in the standard arm, and is retained in place by a nut 55. A set screw 56 passes through the upper end 65 of the stirrup and engages the upper edge of the standard. In order to insure an intimate frictional engagement of the rear end of the standard arm with the inner surface of the friction plates, the rear end of the 70 standard arm is provided on its opposite sides with ribs 57-58 having flat faces 59 extending the entire width of the arm and which engage the inner surfaces of the friction plates.

75

To adjust the angular position of the standard with relation to the beam, for the purpose of varying the pitch or suction of the plow, the nut 55 is loosened which permits the standard to be raised or lowered as 80 may be desired and when properly adjusted the nut is again tightened with the effect of forcing the friction plates into snug frictional contact with the opposite sides of the standard arm and retaining it against accidental movement or displacement. The set screw 56 is then adjusted so as to engage the upper edge of the standard and prevent its upward movement and displacement. It will thus be observed that the pitch or suction of the plow may be readily varied to 90 suit different soils or conditions of the soil. In the event the plow should strike an obstruction which would be liable to break or injure the plow point or other part of the plow, the abnormal strain on the plow would operate to break the break pin and permit the plow to rotate on the bolt 54 and thus ride over the obstruction and thereby preserve the plow against breakage or injury. 95 Whenever the soil is such that no obstructions of a character to injure the plow are liable to be encountered, the forward end of the standard arm may be secured to the beam by a bolt 60.

100

105

It is evident that many slight changes might be resorted to in the relative arrangement of parts shown and described without

departing from the spirit and scope of my invention. Hence I would have it understood that I do not wish to confine myself to the exact construction and arrangement of parts shown and described but

Having fully described my invention what I claim as new and desire to secure by Letters-Patent, is:—

1. The combination with a plow beam, of a standard provided with a forwardly projecting arm having an open slot formed in its upper edge, and a clamping bolt extending through the beam and said slot.
2. The combination with a plow beam and a standard provided with a forwardly projecting arm, of friction plates interposed between the standard arm and plow beam sections, the forward ends of the friction plates being formed to project below the beam sections, and a break pin supported in the friction plates below the plow beam.
3. The combination with a plow beam consisting of two sections and a standard provided with an elongated slot in its upper end, of friction plates secured to the plow beam sections at respective sides of the standard, a stirrup having its arms interposed between the standard and friction

plates, and a bolt passing through the plow beam sections, stirrup arms, friction plates, and elongated opening in the standard.

4. The combination with the plow beam sections and friction plates secured thereto, of a standard provided with a forwardly projecting arm formed with flat surfaces on its front and rear ends which engage the friction plates on the beam sections, and clamping bolts extending through the plow beam sections, friction plates and front and rear ends of the standard arm.

5. In a gang plow, the combination with a plow beam, a standard provided with a forwardly projecting arm, and friction plates secured to the plow beam sections at respective sides of standard arm, of a break pin, means for firmly clamping together the forward end of the standard arm, friction plates and plow beam sections.

In testimony whereof, I have signed this specification in the presence of two subscribing witnesses.

NORMAN I. MILLIKEN.
